CLAIM

The ornamental design for an information transmitter, as shown and described.

DESCRIPTION

FIG. 1 is a perspective view of an information transmitter showing my new design;

FIG. 2 is a front elevational view thereof;

FIG. 3 is a left side elevational view thereof; and

FIG. 4 is a left side elevational view thereof in the closed condition.

FIG. 5 is a perspective view of another embodiment of an information transmitter showing my new design;

FIG. 6 is a front elevational view thereof;

FIG. 7 is a left side elevational view thereof; and,

FIG. 8 is a left side elevational view thereof in the closed condition.

The even broken lines showing in the drawings illustrate unclaimed portions of the information transmitter and form no part of the claimed design. The dot-dash broken lines which define the bounds of the claimed design form no part thereof.
